UNITED STATES PATENT OFFICE.

JOHN H. TOWERS, OF BALSAM LAKE, WISCONSIN.

DEAD-CENTER DEVICE.

Application filed May 15, 1926. Serial No. 109,401.

The invention relates to an improved mechanical movement designed to be employed for converting reciprocatory movement into movement of rotation, the object of the invention being to provide an assemblage of mechanical elements which will cooperate to overcome dead centers.

The invention is applicable for use in connection with steam engines, gas engines, 10 windmills, hand operated devices, or in any relation wherein it is desired to overcome dead centers.

An illustrative embodiment of the invention is shown in the accompanying drawings 15 in which

Figure 1 is a side view of the device shown connected at one end to a reciprocating piston and at the other to a wheel.

Figure 2 is an end view of the same.

20 Figure 3 is a fragmentary view, similar to Figure 1, but showing a modification.

In the drawings the reference numeral 10 denotes a suitable fixed base or support, the numeral 11 denotes a wheel rotating about a fixed center 12 and the numeral 13 denotes a fixed cylinder having a reciprocating piston 14 provided with a piston rod 15. It is desired to transform the reciprocatory movement of the piston rod 15 into rotary movement of the wheel 11 by a suitable assemblage of mechanical elements which are so related that they effectively overcome dead centers.

Pivoted connected to the rod 15 as at 16 35 is a connecting rod 17, which at its opposite end is pivoted as at 18 to the vertical arm 19 of a T crank, the horizontal arm 20 of which is connected to the fly wheel 11 by means of the crank pin 31. The T crank is pivoted at 21 to an oscillating rocker arm 22 which is pivoted as at 23 to the stationary support 10, as shown. A suitable spiral 40 spring 24 connects the fixed pivot 23 to the oscillating pivot 18 at the juncture of the crank arm 22 and the arm 19 of the T crank.

The rocker arm 22 is adapted to swing to and fro as a pendulum, oscillating about the fixed pivot 23, and carries with it the oscillating pivot 21 which swings in the arc of 45 a circle, indicated by the arrows.

Assuming now that the mechanism is in the position shown in full lines in Figure 1, and that the spring 24 is under tension, the piston rod 15 is moved to the right in the 50 direction of the arrow. Due to the downward pressure produced by the spring 24 on

the pivot 21, a movement of the wheel 11 in a counterclockwise direction, as indicated by the arrow results, and the crank pin 31 is carried past the dead center position, due to 60 the action of the spring 24 which is operative at the moment when the piston begins its reverse stroke. One position which would normally be a dead center position, if the spring 24 were absent is indicated in the dotted lines, this being likewise the position in which the piston 14 has reached its extreme limit to the right and begins to reverse. However, due to the energy which has been 65 stored in the spring 24, the wheel is snapped 70 past the dead center position, the force of the spring being greatest at the time the force applied by the piston is least. The wheel therefore continues to rotate uniformly in one direction, being carried past 75 each dead center position by the action of the spring.

Obviously if the force operating upon the pivot 21 were reversed, as for instance, if a compression spring were substituted for the 80 spring 24, the direction of movement of the wheel 11 would be reversed, but the action in overcoming dead center would be the same as before.

Likewise, it will be found that where the 85 reciprocating force is applied to the lower end of the T crank, as where the link 17 is connected to the lower end of the arm 19, direction of rotation of the wheel 11 is reverse to that in which the force is applied 90 above the pivot 21. In other words, the direction of rotation may be reversed either by reversing the direction of force of the spring 24 on the crank arm 19 or by changing the point of application of the reciprocating force from a position above to a 95 position below the pivot connecting the rocker arm with the T crank.

A modification of the invention is indicated in Figure 3, wherein a piston and cylinder, using compressed air, is substituted for the spring 24. The wheel 11, and the mechanism for producing reciprocating movement are omitted in this figure, as it is understood that they operate in the manner 100 described in connection with Figure 1. In Figure 3, the reference numeral 19' indicates the upper arm of the T crank. The arm 22' pivoted at 23' is the oscillating crank, corresponding to the crank 22 shown in Figure 105 1. In place of a spiral spring acting upon the T crank and producing a lifting or a

downward pressure upon the pivot 21' acting at an angle to the arm 20', a piston and cylinder may be employed by means of which compressed air or other fluid, performs the 5 function of the spring. As shown, a cylinder 30, having air inlets 31 and 32 is provided with a piston 33, the rod 34 of which is connected by means of a suitable crank arm 35 to the upper end of the T crank, as at 18'.
16 The operation of this device is the same as that described in connection with Figure 1. In order to reverse the direction of movement of the wheel (not shown) it is only necessary to reverse the direction of the pressure 15 acting upon the pivot 21', this being accomplished by introducing compressed fluid above or below the piston 33 as desired.
Many changes may be resorted to without departing from the spirit of the invention.
20 For example, the T crank is not essential to the operation of the device, as any crank having arms set at angles to each other may be employed in a similar relation. Likewise, in place of the spring 24 or the compressed 25 air cylinder, any means may be employed which will produce a pressure upon the oscillating pivot, which pressure acts at an angle to the arm of the crank which is attached to the wheel or rotary element.

30 What I claim is:—

1. A device for overcoming dead centers comprising in combination with a fixed pivot, a rocker arm oscillating about said fixed pivot, a rigid right angle crank pivotally 35 connected to the oscillating end of the rocker arm, a rotary element connected to one end of said rigid crank, and a source of power operating another arm at an angle thereto, and means for applying pressure to said

crank, the direction of pressure determining 40 the direction of movement of the rotary element.

2. A mechanical movement for translating reciprocatory into rotary movement, designed to overcome dead centers, comprising a 45 rocker arm oscillating about a fixed pivot, a rigid crank having arms set at angles to each other, one arm being connected to a rotary element, said crank being pivoted at the juncture of the arms thereof to the oscillating 50 end of the rocker arm, and means for exerting pressure upon the oscillating pivot of said crank.

3. A device for overcoming dead centers, comprising a fixed pivot a rocker arm oscillating about said fixed pivot, a bell crank pivotally connected to the oscillating end of the rocker arm, one arm of said bell crank being connected to a rotary element and the other arm adapted to be operated from a suitable source of power, and resilient means interposed between the fixed pivot of said rocker arm and one end of said bell crank.

4. A mechanical movement for translating reciprocatory into rotary movement or vice versa comprising fixed pivot, a rocker arm oscillating about said fixed pivot, a bell crank pivotally connected to the oscillating end of the rocker arm, one end of said bell crank being connected to a reciprocatory element and the other to a rotary element, and a spring connecting the fixed pivot of said rocker arm to one end of said bell crank.

In testimony whereof I affix my signature.

JOHN H. TOWERS.
